UNITED STATES PATENT OFFICE.

ROBERT B. CRAIG AND ALBERT COFFMAN, OF KANSAS CITY, MISSOURI, ASSIGNEES TO THE AUTOMATIC VENDING MACHINES COMPANY, OF KANSAS CITY, MISSOURI, A CORPORATION OF THE TERRITORY OF NEW MEXICO.

RIBBON-FEEDING MECHANISM.

964,851.

Specification of Letters Patent. Patented July 19, 1910.

Original application filed April 12, 1909, Serial No. 489,457. Divided and this application filed August 24, 1909. Serial No. 514,457.

To all whom it may concern:

Be it known that we, ROBERT B. CRAIG and ALBERT COFFMAN, citizens of the United States, and residents of Kansas City, in the county of Jackson, State of Missouri, have invented certain new and useful Improvements in Ribbon-Feeding Mechanism, of which the following is a specification.

The present invention relates to a ribbon feeding mechanism for coin controlled machines, and is particularly adapted to that type of machine disclosed in our copending application dated April 12, 1909, and bearing Serial No. 489,457, and of which case the present application forms a division.

The purpose of the invention is to provide a mechanism of the type in question which embodies a minimum number of parts and which shall be positive in its operations and at all times keep the ribbon at the proper tension.

The further purpose of the present invention is to provide the mechanism with such means as will render the same entirely automatic in its operations, and which automatic means is such that it effects the reversal of the ribbon on the unwinding of either spool, and which in its time for shifting occurs just at the moment that either spool has become entirely unwound.

With these as its essential advantages, the invention embodies other points of advantage which will be clear in the course of the following extended description, and the points of novelty thereof are set forth in the appended claims.

In the accompanying drawing which illustrates the preferred structure of the mechanism, Figure 1 is a side elevation thereof, and, Fig. 2 is a top plan view of the same.

Referring to the parts of the mechanism in detail and wherein like numerals of reference indicate corresponding parts in both views shown, 73 indicates the ribbon which is wound upon a pair of bobbins 132 each provided with a ratchet 133 with which cooperate a pair of oscillating arms 134 and 134' whose ends are designed to constitute pawls 135. The arms 134 and 134' are pivotally secured at a common point 136 on a disk 137 that is in turn centrally pivoted to a reciprocating bar 138, which bar is mounted upon the upper ends of a pair of parallel

arms 140 projecting from rocking shafts 141, one of which has an arm 142 connected by a pitman 143 with that part of the machine which effects the actuation of the ribbon mechanism. The disk 137 is provided with a pair of notches 145 adapted to receive a detent 146 whose function is to hold said disk 137 against rotation during the reciprocation of the bar 138 and thereby keep one of the pawls 135 in position to engage the teeth of its respective ratchet for actuating the same, and at the same time to keep the opposite pawl free from engagement with its ratchet.

When the ribbon is wholly unwound from the bobbin opposite to that upon which it is being wound, and its end is anchored fast to the empty bobbin, the resistance of the engaged ratchet with its pawl causes the active arm 134 or 134' to pull upon the disk 137 and partially rotate the same. The detent 146 then engages with the other notch 145 and thereby brings the opposite pawl into engaging position with its respective ratchet, and at the same time releases the just active pawl and thus reverses the direction of feed of the ribbon. This operation of the ribbon reversing means occurs automatically whenever the ribbon has reached the limit of its feed in one direction.

Having thus described our invention, what we claim as new and desire to secure by Letters Patent, is:

1. A ribbon feeding mechanism comprising winding spools, ratchets having driving connection with said spools, a reciprocating bar, having a pair of independent arms pivoted thereon and provided with pawl members, said arms being supported at their free ends by said ratchets, means for shifting the position of said arms whereby the pawls may alternately engage the ratchets of the spools, and means for actuating said reciprocating bar whereby to feed the ribbon.

2. A ribbon feeding mechanism comprising winding spools, ratchets having driving connection therewith, a reciprocating bar having a disk pivoted thereon, a pair of arms pivoted to said disk and provided with pawl members, said pawls adapted to alternately engage the ratchets of the spools, means for holding said pawls in operative and inoperative position, and means for

actuating the reciprocating bar whereby to feed the ribbon.

3. A ribbon feeding mechanism comprising winding spools, ratchets having driving connection therewith, a reciprocating bar having a disk pivoted thereto intermediate its ends, a pair of arms mounted on a common pin carried by said disk, said arms having their opposite ends designed to provide pawl members, said pawls adapted to alternately engage the ratchets of the spools, means for holding said pawls in operative and inoperative position, and means for actuating the reciprocating bar whereby to feed the ribbon.

4. A ribbon feeding mechanism comprising winding spools, ratchets having driving connection therewith, a reciprocating bar having a disk pivoted thereon, a pair of arms pivoted on a common pin mounted on said disk, said arms having their opposite ends designed to provide pawl members, said pawls adapted to alternately engage the ratchets of the spools for feeding the

ribbon, a detent engaging said disk whereby to hold said pawls in operative and inoperative position, and means for actuating the reciprocating bar whereby to feed the ribbon.

5. A ribbon feeding mechanism comprising winding spools, ratchets having driving connection therewith, a reciprocating bar having a disk mounted thereon, a pair of arms pivoted on a common pin mounted on said disk and provided with pawl members, said pawls adapted to alternately engage the ratchets of the spools on the tensioning of the ribbon on the unwinding of one of the spools, said disk provided with a detent for holding the said pawls in operative and inoperative position and permitting the same to have shifting movement.

The foregoing specification signed at Dayton Ohio this 2nd day of July, 1909.

ROBERT B. CRAIG.
ALBERT COFFMAN.
